TURBINE

Gustav Karl William Boestad, Lidingo, and Teodor Immanuel Lindhagen, Stockholm, Sweden, assignors, by mesne assignments, to Jarvis C. Marble, New York, N. Y., Leslie M. Merrill, Westfield, N. J., and Percy H. Batten, Racine, Wis., trustees

Application January 25, 1947, Serial No. 724,278
In Sweden November 26, 1946

7 Claims. (Cl. 253—69)

1

The present invention relates to turbines and has particular reference to elastic fluid turbines. More particularly, the invention relates to multiple stage turbines, and still more particularly it relates to such turbines in which at least the major part of the energy of the motive fluid is extracted by reaction and which are ordinarily classified as reaction turbines.

It is characteristic of turbines that a certain amount of leakage past the ends of the blades of a blade ring is unavoidable in the case of any blade ring mounted on one part of the turbine between which and another part of the turbine there is relative rotation. Thus in the case of an axial flow turbine, there is leakage past the outer circumference of the rotor blade rings and the stationary casing or stator. Likewise there is leakage between the inner circumference of the stationary or guide blade rings carried by the stator and the adjacent part of the rotor. Similarly, there is leakage past the free ends of the blade rings of a radial flow turbine of the Ljungstroms type and the disc or rotor carrying the rings of oppositely rotating blades.

The motive fluid leaking past any such blade ring flows to and through the next succeeding ring, but as will hereinafter be more fully explained, this fluid has different flow characteristics than that of the main body of fluid discharged from between the blades of the ring and has a deleterious effect on the flow of fluid through the next succeeding ring, which consequently adversely affects the efficiency of that ring.

The adverse effect of leakage has long been recognized in the turbine art and many expedients have been employed to reduce the amount of such leakage. The most practical and substantially universal method of reducing such leakage is the provision of sealing strips in the form of fins or the like, notched surfaces, etc., all designed to increase the resistance to flow of the leakage fluid and usually referred to generally as labyrinth packing. Such packing has proved to be reasonably efficient, but none has yet been developed sufficiently efficient to eliminate leakage flow.

The general object of the present invention is to increase turbine efficiency by an improved construction which is effective to not only reduce

2

the deleterious effect of leakage fluid unavoidably flowing to a succeeding turbine ring from a preceding ring, but also to as far as possible convert such flow in the succeeding ring to a useful purpose, so that the previous negative effect on efficiency of leakage fluid is not only eliminated but a positive effect therefrom is secured.

The manner in which the above general object and other and more detailed objects of the invention are secured, as well as the advantages to be derived from its use, will be hereinafter more fully explained in conjunction with the accompanying drawings forming a part hereof in which:

15 Fig. 1 is a more or less diagrammatic longitudinal section of a portion of the blade system of an axial flow turbine embodying the principles of the invention;

20 Figs. 2 to 4 inclusive are sections taken on the respectively numbered section lines of Fig. 1;

Fig. 5 is a view similar to Fig. 1 showing part of the blade system of a radial flow turbine embodying the principles of the invention;

25 Fig. 6 is a section taken on the line 6—6 of Fig. 5;

Fig. 7 is a fragmentary section showing part of a different form of blade structure embodying the invention; and

30 Fig. 8 is a section taken on the line 8—8 of Fig. 7.

Referring now more particularly to Figs. 1 to 4, the invention in one of its structural embodiments is illustrated as applied to an axial flow turbine, a portion of the blade system of which is more or less diagrammatically illustrated in the drawings. In Fig. 1 the rotor structure of the turbine is indicated at 10 and the stator structure is indicated at 12. Two rows of stator or guide blades 14 and 16 are shown, the inner ends of these blades being secured respectively to annular shrouds 18 and 20. At their outer ends, blades 14 and 16 are shown as connected to the stator structure 12 which carries the respective blade rings. Blades 14 and 16 may be attached at their ends to the stator structure and to the inner shrouds by any known form of construction, as by welding or by one or another form of blade root received in a recess or channel in the member to which the blade is attached, and since the specific construction em-

ployed for attaching the blades is not important to the present invention the details of the method of attachment have been omitted for the sake of clarity.

A ring of moving or rotor blades 22 is located between the guide blades 14 and 16, the rotor blades being attached at their radially inner or root ends to a disc-like flange 24 on the rotor and at their outer ends being shown as connected by the usual shroud ring 26. As in the case of the guide blades, the specific manner of attachment of the blades 22 is immaterial to the present invention and has not been indicated.

The direction of flow of motive fluid through the blade system is assumed to be from left to right as viewed in Fig. 1 and as indicated by arrow 28.

Referring now to Fig. 2, the normal path of flow of the motive fluid passing through the blade system is shown, the direction of rotation of the rotor being assumed to be counterclockwise as viewed from the left-hand end of the drawing and as indicated by arrow 30.

Fluid flowing through the guide blade ring 14 is discharged from the outlet side of the ring in the direction of arrow 32, but because of the rotation of the turbine rotor in the direction of arrow 30 the relative inlet angle of the motive fluid to the ring of rotor blades 22 is in the direction of the arrow 34, and as will be seen from the drawing the profile of the blades 22 is designed in accordance with known principles so as to provide for smooth entrance to and flow through the passages between the blades. The fluid is discharged from the rotor blades in the direction indicated by arrow 36, but due to the relative rotation between the rotor blade ring and the next succeeding guide blade ring, the relative angle of entry of the fluid into the passages between the guide ring blades 16 is in the direction of arrow 38. This entrance angle permits smooth entry and flow of the fluid between the guide blades in accordance with known practice.

While the major portion of the fluid discharged from the ring of guide blades 14 flows through the succeeding rotor blade ring in the manner above described, a certain amount of this fluid leaks past the outer circumference of the rotor blade ring through the space 40 between the rotor ring and the stator structure. This leakage is reduced as far as possible by means of any suitable known form of packing which in the present instance has been indicated by labyrinth sealing fins 42 projecting from the shroud ring 26.

The nature of the flow of the leakage fluid is shown in Fig. 3. As will be seen from this figure, fluid discharge from the guide blade ring 14 leaves this ring in the direction as indicated by arrow 32. In this case, however, the fluid leaking past the end of the ring of rotor blades 22 does not have its peripheral component of flow reversed by its flow between the rotor blades, but continues to flow across the leakage space 40 in the same sense as it enters, as indicated by arrows 32a. The result is that the leakage fluid is discharged from the leakage space to the next succeeding blade ring with a peripheral component of flow as indicated by arrow 33b, which is in the same sense as the angle of discharge from the preceding guide blade ring. In other words the peripheral component of flow is not reversed as is the case with the fluid passing through the proper channels in the rotor blade ring.

As will be apparent from inspection of Fig. 3, 75

the direction of entry of this leakage steam to the ring of guide blades 16 is such that if the fluid impinged blades having the normal blade profile designed to receive fluid discharged from the preceding blade ring with the proper relative inlet angle indicated by arrow 38, the leakage steam would impinge on the back rather than the front faces of the blades. With prior forms of construction this is what occurs and the impingement of the leakage steam upon the blades with an entrance angle materially different from the normal entrance angle creates eddy currents and like disturbances which impair the efficiency of the system. This loss, due to interference with or modification of the normal flow by leakage fluid at the leakage end zone of the blades is a definitely established factor in turbine performance and is ordinarily taken into account by the use of empirically established formulae when calculating the efficiency of a turbine design.

In accordance with the present invention this loss, occasioned by entry of leakage fluid to a turbine ring with an angle of entrance other than the normal angle, is reduced if not entirely eliminated and the flow of leakage fluid utilized, by providing special channels at the end zone of the blade ring where leakage fluid from a preceding blade ring enters, which zone may for convenience be referred to as the leakage end zone. In the present embodiment, these channels are provided in the guide blade rings by removing the leading edge portions of the guide blades at the ends where they are attached to the stator structure to provide channels 44 and 46 which are relatively narrow longitudinally of the blades and which as will be seen more clearly from Fig. 3 provide for smooth guidance into and flow through the passage between the guide blades of leakage fluid entering the blade ring with an entrance angle entirely different from that with which the main body of fluid is discharged from the blades of the preceding blade ring.

Considering the nature of the leakage flow past the inner shrouds of the stator rings as illustrated in Fig. 4, it will be apparent that the leakage fluid flowing through space 48 between the shroud 18 and the rotor 10 will pass the ring of guide blades 14 with a direction of flow as indicated by arrow 36, which represents the direction of discharge from the blades of the preceding row of moving rotor blades. Since this leakage fluid does not have the sense of its peripheral component of flow reversed by passage between the guide blades 14, its direction of discharge to the ring of rotor blades 22 will also be with substantially the same peripheral component, and as will be apparent from Fig. 4, if no provision were made for taking care of this fluid, it would impinge on the backs of the blades 22.

Since the moving rotor blades are subject to tension, particularly at the root ends, due to centrifugal force to which the stator blades are not subjected, it may in some instances be undesirable to weaken the rotor blades by diminishing the sectional area to provide the desired channels for leakage fluid, and in the embodiment illustrated this is avoided while essentially accomplishing the desired object through the provision of special channels 50 formed in the rotor flange 24 to which the blades are secured. As will be evident from the figure, such channels serve to smoothly receive and guide the leakage fluid which in its course of flow reaches these channels before it reaches the inner periphery

of the blades 22. If design conditions permit, the entrance portions of the blades 22 may also be removed as indicated by the dotted lines 52 to provide blade profiles at the leakage end zone similar to those provided on the stator blades by the channels 46.

Likewise, if desired, the stator structure may be provided with grooves as indicated by the dotted lines 54 in Figs. 1 and 3. Obviously, either expedient or both combined may be used at the leakage end zone of both stator and rotor blades.

The same principles apply to a radial flow turbine, a part of a blade system of which is shown by way of example in Fig. 5.

In this figure, one of the turbine rotors is indicated at 56 and is shown as carrying blade rings 58 and 60 by means of the usual supporting rings 62 and 64, respectively.

The counter-rotating rotor disc is indicated at 66 and carries blade ring 68 by means of the supporting ring 70. Direction of fluid flow is indicated by arrow 72, and the flow of leakage fluid past the different rings is indicated by arrows 74 and 76. Since all of the blades in this type of turbine are subject to centrifugal force and strength at the roots is desired, the manner of guiding the flow of the leakage fluid is indicated in the embodiment shown as by means of channels 78 formed in the end rings at the leakage end zone of each of the blade rings.

Since the difference in flow between the main body of fluid and the leakage fluid is governed by the same principles as those previously discussed, it will not be necessary to again describe the action which determines the manner in which the special channels for leakage fluid are provided.

The embodiments previously described illustrate constructions in which blade stock of uniform profile may be employed, which from a manufacturing standpoint is frequently advantageous because of minimum cost. The principles of the invention can, however, be equally well if not even more efficiently carried out by providing the special end zone channels for leakage fluid through the medium of blades of special contour having profiles at the leakage end zone different from the normal profile and with the two sections of different profile joined by suitable surfaces curved longitudinally of the axis of the blades. Such construction is illustrated in Figs. 7 and 8, wherein the blades 80 are provided with the normal desired profile, as indicated at 82, along substantially their entire length and are shaped to a different profile 84 at the leakage end zone. These two profiles are joined by suitably curved surfaces indicated at 86 and 88. As will be observed from the figures, the normal profiles 82 are adapted to receive and properly guide the main body of fluid entering the blade ring at the normal relative inlet angle indicated by arrow 90, while the profile 84 at the end of the blade is adapted to receive and properly guide the leakage fluid entering with a different relative inlet angle, as indicated at 92.

From Fig. 8 it will be seen that between the structure 94 to which the blade is attached, and which may be an outer shroud ring or any supporting structure, and the section of the blade indicated at 96 where the normal profile terminates, there is provided between the blades a special channel 98 for guiding the leakage fluid.

We are aware that heretofore it has been common practice to provide twisted or warped blades in axial flow turbines to compensate for differ-

ences in relative inlet angle of portions of the main body of fluid entering the blade system at different radii, and that for that and other reasons blades have been employed which have different profile contours at different radii. Insofar as we are aware, however, no provision has heretofore been made of special channels at the leakage end zone of the blades which provide the flow are materially different configuration than the channels immediately adjacent to the leakage end zone and which have a configuration designed to properly receive and guide motive fluid discharged from a preceding blade row.

From the foregoing it will be evident that the principles of the invention may be accomplished by various different structural expedients and that the directional relation between the special channels for leakage fluid and the main channels may differ widely with different specific turbine designs, depending upon the relation between the relative periphery velocity between adjacent blade rows, the velocity of the fluid through the blade rows, the outlet angles of the blades and other factors. It is, therefore, to be understood that the invention is not limited to the structure herein disclosed by way of example but is to be considered embracing all forms of structure falling within the scope of the appended claims.

What is claimed is:

1. A multiple stage turbine comprising two relatively rotatable carrying members, a first series of blade rings carried by one of said members, a second series of blade rings carried by the other of said members, the rings of said two series alternating and providing between the blades thereof a main expansion passage for flow of motive fluid, the blades of said first series being positioned to discharge fluid at an outlet angle having a peripheral component of a given sense with respect to the axis of rotation of the turbine, the blades of said second series being positioned to discharge fluid at an outlet angle having a peripheral component opposite to said given sense, and means providing channels through said rings adjacent to the ends of the blades connected to the respective carrier members, said channels being in open communication throughout their length with said main passage and having inlet portions located to receive leakage fluid passing between the preceding blade ring and the carrier member with respect to which said preceding blade ring is relatively rotatable, and said channels having inlet angles directed in the same sense with respect to said axis of rotation and of substantially the same magnitude as the outlet angles of the blades of the next preceding blade ring of the same series.

2. A blade system as defined in claim 1 in which the means providing said channels comprises blade end portions of different profile than that of the portions of the blades traversing said main passage.

3. A blade system as defined in claim 2 in which the profiles of said end portions of the blades are formed with leading edges recessed with respect to the leading edges of the major portions of the blades traversing said main passage.

4. A blade system as defined in claim 1 in which said carrying members are grooved to form said channels.

5. A blade system as defined in claim 1 in which said channels are formed in part by grooves in said carrying members and in part by end portions of said blades of different profile than

that of the major portions of the blades traversing said main passage.

6. A blade system as defined in claim 1 in which said carrier members consist of a stator and a rotor carrying rings providing an axial flow main passage and in which said channels are provided at the radially inner ends of the rotor blades and at the radially outer ends of the stator blades.

7. A blade system as defined in claim 1 in which said blade carrying members consist of 10 two oppositely rotatable rotors carrying axially extending blades providing a radial flow main passage and in which said channels are provided

in successive blade rings at alternating axially opposite sides of said passage.
